ILLUMINATION MEANS FOR HANDBAGS AND
THE LIKE

William A. Smith, Charlotte, N. C.

Application July 19, 1941, Serial No. 403,144

3 Claims. (Cl. 240—6.45)

This invention relates to illuminating means for luggage, such as satchels, toilet cases, purses and the like, and more especially to a device of this character in which a pivoted latch serves a dual purpose, i. e., holding the satchel in a closed position and as a switch which controls the illumination of the satchel.

It is another object of this invention to provide a satchel, purse or the like having a pivoted combination battery casing and latch, which latch will serve to hold the satchel closed when rotated to one position and which will complete a circuit to illuminate the interior of the satchel when rotated to another position. Such a structure will greatly facilitate the illumination of satchels and the like because the same means which controls the latching also controls the illumination.

Some of the objects of the invention having been stated, other objects will appear as the description proceeds, when taken in connection with the accompanying drawing, in which—

Figure 1 is an isometric view of a hand bag on which my improved illuminating means is installed;

Figure 2 is an enlarged transverse sectional detail view taken along the line 2—2 in Figure 1;

Figure 2A is an isometric view of the adjustment shims;

Figure 3 is an enlarged longitudinal sectional view taken along the line 3—3 in Figure 1;

Figure 4 is a transverse sectional detail view similar to Figure 2, but showing a slightly modified form of the invention.

Referring more particularly to the drawing, the numeral 10 broadly designates a ladies' handbag comprising a pair of frames 11 and 12 which are pivotally secured to each other as at 14. These frames have secured thereto as at 15 and 16, respectively, edges of a suitable flexible material 17, which forms a receptacle. The frame 11 has suitable eyelets 18 extending upwardly therefrom to which the ends of a suitable strap 19 are attached, said strap being employed as a handle.

Latching means

A rigid projection 20 is provided on the upper free edge of the frame 12. This projection has a beveled upper edge 21 which engages a second beveled edge 22 of a hook member 23 as the frames 11 and 12 are rotated to closed position, said hook member 23 being integral with the upper end of a resilient metallic strap 24. Strap number 24 extends upwardly from the free upper edge of frame 11. When latching the frames

11 and 12 in closed position, the beveled surface 21 on rigid projection 20 will contact the beveled surface 22 and thereby cause the hook member 23 to rotate sufficiently about bendable strip 24 as an axis to permit the lower edge of the hook member 23 to pass over the upper edge of the projection 21. After passing over this upper edge of the projection, the inherent resiliency in the strap member 24 will cause the hook member 23 to assume the upright latched position as shown in Figure 2. It will be noted by referring to Figure 2 that the metallic strap member 24 extends downwardly into a cavity 25 in the frame 11 and is bent in the form of a reverse curve as at 26 forming a spring construction which permits the strap member to yieldingly move out of the cavity 25 a slight amount while it is being bent or tilted to permit the projection 20 to pass beneath hook member 23.

Illuminating device and circuit

Also the hook member 23 has integral therewith, a suitable battery casing 27, preferably made of a suitable waterproof material. Disposed within the casing is a conventional battery cell 28 which battery has a cardboard or insulation cover 29, a metallic inner cover such as zinc and the like 30, and a suitable electrolytic compound 31 on the interior of the inner cover. One end of the casing 27 has a cover 32 threadably mounted thereon, said cover serving as a means for holding a suitable coiled spring 33 against one end of the battery cell 28 to serve as a ground connection.

The other end of casing 27 has a cap 34 threadably secured thereon, said cap having an insulation disk 35 disposed therein, which disk has one leg of an L-shaped insulation strip 36 resting against one face thereof. This L-shaped strip 36 has secured thereto as at 37 an L-shaped conductor strip 38, said strip having a contact terminal 39 extending from its other end to the exterior of the casing 27. Contact 39 is disposed in close proximity to the base of a light bulb 40, which bulb is threadably secured in frame 11 so that the illuminating means will be disposed normally on the interior of the handbag 10. This light bulb has a filament 41 therein, one end of which is connected as at 41a on the exterior of the bulb and its other end being grounded in a conventional manner as at 42 to the metallic base of the bulb.

It is to be borne in mind that the point 41a is exposed to the exterior of the purse and is located in the path adapted to be travelled by

the terminal 39 when it is rotated in a clockwise manner in Figures 1 and 2. In other words, when the casing 27 together with its associated latch 23 and terminal 39 are rotated in a clockwise manner to unlatch the purse, the contact 39 may be caused to make connection with one end of filament 41 to close the circuit between points 39 and 41a. This circuit is conventional, and comprises ground wire 33, battery cell 28, contact 37, conductor wire 38, terminal 39, filament 41, and ground 42.

The distance between filament point 41a and the terminal 39 may be varied as desired. For example, it may be desired to unlatch the purse without closing the electrical circuit between points 39 and 41a. In such cases, a substantial clearance would be required between these two points. In order to make it possible to vary the distance between the terminal 39 and point 41a, suitable shims 44 are disposed around the base 20 of the bulb 40 and on the inside of the frame 11. These shims limit the upper position of point 41a.

Figure 4 shows a slightly modified form of the invention in which similar parts will be given like reference characters and a description will be made only of the parts which differ in construction. This form of the invention shows the frame 11 having pivotally secured thereto as at 45, a casing 27a, said casing 27a having a conventional battery cell 28 therein. The casing 27a has integral therewith a conventional latch 23 which engages projection 20 when the purse is closed. Disposed between the pivot point 45 and the free end of the latch 23 is a terminal 39a, which is disposed directly above point 41a of bulb 40. A torsion spring 46 fits around the pivot shaft 45, and one end of this spring contacts the casing 27a and the other end contacts the frame 11, thereby normally rotating the casing in a counterclockwise manner in Figure 4 about shaft 45. The spring serves to hold the purse in latched position and also urges terminal 39a toward point 41a. However, when the parts are in latched position as shown in Figure 4, there is sufficient clearance between the contact 39a and the point 41a to prevent contact from being made. Upon the unlatching of the purse, the spring 46 will close the circuit, unless it is held open by the user. Therefore, it is seen the interior of the purse will be automatically illuminated when it is opened, unless the user manually holds the terminal 39a out of contact with the filament point 41a.

In the drawing and specification, there has been set forth a preferred embodiment of the invention, and although specific terms are employed, they are used in a generic and descriptive sense only and not for purposes of limitation, the scope of the invention being set forth in the following claims.

I claim:

1. A handbag having a frame comprising first and second substantially U-shaped frame members pivoted to each other at their free ends and

being adapted to be swung apart to form an opening in the handbag, a metallic casing pivotally secured to the first frame member and having latching means for engaging the second frame for holding the handbag in closed position, the first frame having a contact point on the exterior thereof, a light bulb mounted on the inside of the handbag and being electrically connected to the contact point, a battery within the casing, a contact on the exterior of the casing and being connected to one side of the battery and also insulated from the metallic casing, the other side of the battery being connected to the casing, whereby when the handbag is opened and the casing is swung on its pivot the contact on the casing will engage the contact on the first frame and illuminate the bulb.

2. A handbag having a frame comprising first and second substantially U-shaped frame members pivoted to each other at their free ends and being adapted to be swung apart to form an opening in the handbag, a metallic casing pivotally secured to the first frame member and having latching means for engaging the second frame for holding the handbag in closed position, the first frame having a contact point on the exterior thereof, a light bulb mounted on the inside of the handbag and being electrically connected to the contact point, a battery within the casing, a contact on the exterior of the casing and being connected to one side of the battery and also insulated from the metallic casing, the other side of the battery being connected to the casing, whereby when the handbag is opened and the casing is swung on its pivot the contact on the casing will engage the contact on the first frame and illuminate the bulb.

3. A handbag having a frame comprising first and second substantially U-shaped frame members pivoted to each other at their free ends and being adapted to be swung apart to form an opening in the handbag, a metallic casing pivotally secured to the first frame member and having latching means for engaging the second frame for holding the handbag in closed position, the first frame having a contact point on the exterior thereof, a light bulb mounted on the inside of the handbag and being electrically connected to the contact point, a battery within the casing, a contact on the exterior of the casing and being connected to one side of the battery and also insulated from the metallic casing, the other side of the battery being connected to the casing, whereby when the handbag is opened and the casing is swung on its pivot the contact on the casing will engage the contact on the first frame and illuminate the bulb, and tension means normally urging the two contact points towards each other and also acting to hold the two frames in latched position.

4. A handbag having a frame comprising first and second substantially U-shaped frame members pivoted to each other at their free ends and being adapted to be swung apart to form an opening in the handbag, a metallic casing pivotally secured to the first frame member and having latching means for engaging the second frame for holding the handbag in closed position, the first frame having a contact point on the exterior thereof, a light bulb mounted on the inside of the handbag and being electrically connected to the contact point, a battery within the casing, a contact on the exterior of the casing and being connected to one side of the battery and also insulated from the metallic casing, the other side of the battery being connected to the casing, whereby when the handbag is opened and the casing is swung on its pivot the contact on the casing will engage the contact on the first frame and illuminate the bulb, and tension means normally urging the two contact points towards each other and also acting to hold the two frames in latched position.

WILLIAM A. SMITH.
